UNITED STATES PATENT OFFICE.

EDWARD KRAMER, OF MISHAWAKA, INDIANA.

HAND-COVERING.

1,387,728.

Specification of Letters Patent. Patented Aug. 16, 1921.

Application filed February 20, 1920. Serial No. 360,076.

To all whom it may concern:

Be it known that I, EDWARD KRAMER, a citizen of the United States, residing at Mishawaka, in the county of St. Joseph and

5 State of Indiana, have invented certain new and useful Improvements in Hand-Coverings, of which the following is a specification.

This invention relates to improvements in 10 hand coverings and more particularly to an improved glove especially designed for wear by those engaged in placer mining although it is not restricted to this use as it possesses advantages which recommend it to all who 15 are required to handle tools and particularly such tools as shovels, picks, and the like.

It is a well known fact that the human hand normally assumes a more or less cupped condition as distinguished from a condition 20 in which the fingers would be substantially straight and the palm practically flat, and, of course, when the hand is engaged in holding any material in the palm or in grasping the handle of any tool, its assumes this condition to an even more marked degree. Notwithstanding this fact it has heretofore been customary to manufacture all gloves with substantially straight or flat palm and finger portions so that when the hand is naturally 25 cupped to hold any material therein or to grasp the handle of a tool, the palm of such a glove will become wrinkled or bulged, thus greatly lessening the capacity of the hand and causing discomfort and annoyance 30 through the wrinkles being pressed against the surface of the palm. Therefore, the invention has as its object to provide a glove so constructed that the palm and finger portions thereof will initially be of a shape to 35 substantially conform to the cupped contour of the human hand with the result that when the hand is employed in holding any material as, for example, when examining pay 40 dirt in the course of placer mining, the capacity of the hand will not be decreased, and, 45 when the hand is employed in working with tools such, for example, as picks and shovels, the palm and finger portions of the glove will not be appreciably wrinkled to cause 50 discomfort or interfere with the work.

As placer mining renders desirable the use of waterproof gloves, it is another object of the invention to provide a rubber or rubberized glove possessing the features above 55 briefly pointed out.

In the accompanying drawings:

Figure 1 is a perspective view of a glove designed in accordance with the present invention;

Fig. 2 is a vertical longitudinal sectional view through the glove in its normal condition or shape;

Fig. 3 is a transverse sectional view taken substantially on the line 3—3 of Fig. 1.

In the drawings, the numeral 1 indicates 65 in general the palm of the glove, the numeral 2 the back thereof, the numeral 3 the finger stalls, and the numeral 5 the wrist portion of the glove. This latter portion is provided at one side with a gusset 6 and with 70 any suitable buckle or similar device 7 for closing the gusset and drawing the wrist portion snugly about the wrist of the hand to which the glove is applied. However, 75 this is not an essential feature of the invention and if desired the wrist portion might be formed of some elastic material or composition of materials so as to cause it to normally assume a contracted condition and thus snugly fit the wrist. 80

The body of the glove may be formed of any suitable material or composition of materials but preferably the same comprises a foundation 8 of fabric either knitted or woven and the said foundation may be lined 85 or left unlined either as desired. In the manufacture of the glove, the foundation 8 which has been produced by any appropriate method, has applied to its exterior surface a coating of rubber indicated in general by 90 the numeral 9, this coating being vulcanized to the fabric or other material comprising the foundation of the glove so as to become an integral part with the foundation. In this process of coating the foundation, the 95 palm and finger portions of the glove will be molded so as to assume a shape conforming substantially to the cupped contour of the palm and fingers of the human hand when in repose, the longitudinal inward curvature 100 of the palm and finger portions being most clearly shown in Fig. 2 of the drawings and the transverse inward curvature of the palm being best shown in Fig. 3. By reference to these figures it will also be observed that the 105 coating 9 is of greater thickness at the palm and inner sides of the fingers of the glove than at the back thereof so that the palm and inner sides of the finger portions are somewhat stiffer than the back of the glove and, 110

being thicker serve to more adequately protect and cushion the palm of the hand under working conditions while on the other hand the comparative thinness of the back of the glove provides the desired freedom of movement of the hand. Inasmuch as the palm and inner sides of the finger portions are somewhat stiffer than the back of the glove, they will tend to resist opening movement of the hand, but may be readily moved toward each other in the act of grasping a tool. In practice the wrist portion 5 of the glove will likewise be rubberized although the coating of rubber applied to this portion will be relatively thin so as to not in any way interfere with freedom of movement of the wrist.

From the foregoing description of the invention it will be understood that the glove 20 is in the process of manufacture, shaped to conform to the shape of the hand when in repose, the palm and inner sides of the finger portions of the glove being therefore continuously inwardly curved longitudinally of the glove, and the said palm portion being further transversely curved inwardly so that this latter portion initially is of a cupped shape. It will further be evident that in the use of such a glove, a maximum quantity of 25 material may be held in the palm thereof without likelihood of being discharged or dislodged because of wrinkling of the palm as has heretofore been the case in the use of

gloves having initially flat palm portions, and likewise when the hand is engaged in 35 handling tools a firmer grasp may be given the handle of the tool and no discomfort will be caused on account of any wrinkling of the palm of the glove.

It will be understood that the principles 40 of the invention may be embodied in mittens as well as gloves.

Having thus described the invention, what is claimed as new is:

A hand covering initially shaped to conform substantially to the shape of the human hand in repose and therefore having a cupped palm portion and curved finger portions, the said covering comprising a foundation of fabric, and a coating of rubber applied and intimately united thereto and continuously covering the back, palm, and finger portions of the foundation, the coating at the palm and inner sides of the finger portions being considerably thicker than at the back and the outer sides of the finger portions, whereby the relatively thick portion of the coating and its intimate union with the non-elastic fabric foundation at the cupped palm portion and inner sides of the 55 curved finger portions will serve to retain the hand covering in its initially molded shape.

In testimony whereof I affix my signature.

EDWARD KRAMER. [L.s.]
